SYNCHRONOUS BED MOTION FOR PRINTING PRESSES AND THE LIKE

Arthur J. Jenner, Chicago, Ill., assignor to Miller
Printing Machinery Co., Pittsburgh, Pa., a cor-
poration of Pennsylvania

Application February 26, 1946, Serial No. 650,251

26 Claims. (Cl. 74—27)

1

This invention relates to printing presses and more particularly to improved synchronous mechanical bed motion movements therefor, although certain features thereof may be employed with equal advantage for other purposes.

It contemplates more especially the provision of improved instrumentalities to accomplish more effective synchronous bed motion for printing presses and the like with minimum parts, weight, wear, stresses, and strains.

In reciprocating printing beds, the problem of converting rotary to reciprocating motion has been accomplished in numerous ways. Most mechanical movements for this purpose are, for the most part, cumbersome by reason of many parts and the requirement for a heavy cradle which impedes the speed of movement or creates excessive stresses and wear. Furthermore, a larger number of gears are required to accomplish this conversion of motion so that a greater number of gear tooth play points are involved than is necessary or desirable.

One object of the present invention is to simplify the construction and improve the operation of devices of the character mentioned.

Another object is to provide an improved and simplified mechanical movement for more effectively converting rotary to reciprocating bed motion in printing presses and the like.

Still another object is to provide an improved synchronous bed motion for printing presses and the like wherein minimum parts, gears and weights are involved to appreciably reduce wear, stress and gear tooth play points.

A further object is to provide an improved bed motion wherein the instrumentalities are so combined as to provide a substantially straight line of points of wear.

A still further object is to provide bed motion instrumentalities for printing presses and the like that are balanced to insure smooth operation at comparatively high speeds and to accomplish this end with minimum wear.

Still a further object is to provide a balanced synchronous printing press bed motion wherein all diagonal stresses are reduced to a minimum and all appreciable points of wear are along a substantially straight line for uniformity and longevity of operation.

Other objects and advantages will appear from the following description of an illustrative embodiment of the present invention.

In the drawings:

Figure 1 is a plan view of a printing press bed embodying features of the present invention.

2

parts thereof being broken away and shown in section to clarify the showing.

Figure 2 is a side view in elevation of the printing press bed shown in Figure 1, with a rotary printing roller mounted thereon.

Figure 3 is a sectional view in elevation taken substantially along line III—III of Figure 1 with the parts shown in an intermediate position of displacement.

10 Figure 4 is a sectional view in elevation corresponding to Figure 3, with the parts shown in full outline in one extreme position of displacement and in dotted outline in another extreme position of displacement.

15 Figure 5 a perspective view of the sectional channel ring member shown in assembled relation with other parts in Figures 1 and 6.

Figure 6 is a fragmentary sectional view taken substantially along line VI—VI in Figure 1.

20 Figure 7 is a sectional view in elevation taken substantially along line VII—VII of Figure 1.

Figure 8 is a fragmentary sectional view taken substantially along line VIII—VIII of Figure 1.

Figure 9 is a perspective view of a motion 25 transferring lever shown in its assembled association with other parts in Figures 3 and 4.

Figure 10 is a sectional view taken substantially along line X—X of Figure 1.

Figure 11 is a sectional view in elevation taken 30 substantially along line VII—VII of Figure 1 and corresponding with Figure 7, except that the parts are shown in their other shifted extreme position.

Figure 12 is a diagrammatic stroke diagram 35 of the printing bed motion and operating instrumentalities.

Figure 13 is a face view, looking at the face 40 opposite that appearing in Figure 9, and to larger scale, of the motion transferring lever or reversing hook shown in Figure 9, showing the means for operating the movable jaw of the lever.

Figure 14 is a view similar to Figure 13 showing the parts in a different operative position.

The structure selected for illustration is not 45 intended to serve as a limitation upon the scope or teachings of the invention, but is merely illustrative thereof. There may be considerable variations and adaptations of all or part of the teachings depending upon the dictates of commercial practice. The present embodiment comprises a bed frame 10 which has heavy external side members 11—12 cast or otherwise shaped from suitable material to present a rigid framework. A plurality of intermediate table guide 50 grooves 13, 14, 15, and 16, in this instance four,

are provided for support by plate members 17, 18, 19, and 20, respectively (Figure 10). Upper cross members 21—22 and lower cross members 23, 24, 25, 26 and 27 extend between the side and plate members 11—12 and 17—18—19—20 to rigidify the bed frame structure 10.

A flat substantially rectangular printing table 28 is provided with guide rails 29, 30, 31, and 32, in this instance four, which are attached to the underside thereof as complements of the guide grooves 13, 14, 15, and 16, respectively. These complementary guide grooves 13—14—15—16 and rails 29—30—31—32 define the reciprocal path of movement of the table 28 responsive to instrumentalities to be hereinafter described. A rotary printing roller 33 is mounted on a shaft 34 to rotate in synchronism to the reciprocal movement of the table 28. A gear segment 35 is attached to the printing roller 33 to mesh with a rack segment 36 fixed to the reciprocal table 28 to index the position of one relative to the other during each stroke.

The inking or the printing mechanism forms no part of the present invention which concerns itself with the synchronous bed motion instrumentalities. The primary purpose of this bed motion is to reduce the weight of the reciprocating member which is the bed 28 to the greatest practical degree by elimination of the usual heavy hangers and by the use of a single rack 37 which is attached to the underside of the bed 28 to extend longitudinally thereof. Reversal stress is further reduced by carrying the bed 28 over a greater reversal period of distance of the end strokes of the bed 28 which is accomplished through reversing hooks utilized to convert rotary motion into reciprocal motion as will appear more fully hereinafter.

The rack 37 meshes with a split spur gear 38 having a section 39 connected thereto by a channelled ring 40, in this instance of tri-sectional construction (Figure 5) to enable its assembly with the annular grooves 41—42 provided in the bores 43—44 of the split gear 38—39, respectively (Figure 6). This permits the gear 38 to idle on a sleeve 45 having a shaft 46 rotatively journaled therein. The end of the shaft 46 is provided with a key 47 which fits into a key-way 48 provided in the reduced bore 49 of the hub 50 on which the split gear 39 is formed. Consequently, the split gear 38 can idle relative to the gear 39 which has comparatively narrow teeth.

As shown, the sleeve 45 is press-fitted into a bore 51 provided in the upstanding plate member 18 (Figure 6), and a retainer nut 52 engages the threaded projecting sleeve and 53 adjacent the plate member 18, thereby serving as a bearing for the shaft 46. The shaft 46 freely extends through an adjacent upstanding plate member 17 (Figure 11) for journaled support in a bearing 54 provided in the frame side member 11 so that the shaft 46 may extend therebeyond to carry a pinion 55 on its extremity. It should be noted that the shaft 46 rotates as well as axially shifts; however, the pinion 55 only shifts for the extent of the gear 56 of the two adjacently mounted and substantially larger spur gears 56 and 57.

The adjacently disposed spur gears 56—57 are mounted for corresponding rotation on a shaft 58 which is journaled in bearings 59 provided in the frame members 11 and 18 (Figures 1 and 11). The shaft 58 carries a bell crank 60 at its inward extremity and has a gear 61 fixed thereto between the frame member plates 11—17 (Figure 7).

1) to mesh with another gear 62 carried by a stub shaft 63 (Figure 11). The stub shaft 63 is journaled in bearings 64—65 provided in the frame members 11—18. A cylindrical cam 66 is fixed to the stub shaft 63 to operate a cam follower lever 67 pivoted to an ear 68 carried by the frame member plate 17 (Figure 8).

The cam follower lever 67 has a bracket trip 69 (Figures 1 and 8) fixed to its end to fit into the channel 70 of a collar 71 fixed to the rotatable and shiftable shaft 46 to displace the pinion 55 within the limits of the spur gear 56 and the split pinions 38—39 are also displaced for meshing engagement of one or the other with the rack 37. The pinion 38 is always in mesh with a spur gear 72. The spur gear 72 is fixed to a driver shaft 73 journaled in bearings 74 provided in the frame members 11—18. The driver shaft 73 is disposed parallel to the shaft 58, the former being similarly provided with a bell crank 75 at its extremity so that shafts 58—73 through their bell cranks 60—75 oppositely oscillate reversing hooks 76—77 to be hereinafter described.

The outer extremity of the driver shaft 73 has a large spur gear 78 fixed thereto beyond the frame side member 11 to correspond in size and pitch with the spur gear 57 for permanent meshing engagement therewith. A suitable source of power, such as an electric motor and driving pinion (not shown) may be operatively connected to the spur gear 78 to drive the bed motion instrumentalities including the oscillation of the reversing hooks 76—77 and a pinion 79 meshes with the spur gear 78 to rotate a shaft 80 extending across the entire frame 10 and journaled therein to rotatively support a flywheel 81.

The reversing hooks 76—77 each consist of opposed jaws forming a substantially U-shaped cavity 82 with the outer lip 83 somewhat longer than the inward lip 84. One of the jaws 83a of each hook or lever is integral with the body 85 thereof, the other jaw 84a being pivoted thereto as will presently be described. The body 85 of each hook has a boss 86 projecting laterally therefrom to receive a bore 87. Each body 85 terminates downwardly in furcated shanks 88—89 which have circular bearings 90—91 formed integral therewith to receive pins 92 and 93 therethrough. The pins 92—93 are fixedly mounted in the frame member plates 18—19 proximate to the bottom thereof to pivotally support the hooks 76—77.

The movable jaw 84a of each hook is pivoted to the jaw 83a thereof at 106. The jaw 84a is adapted to turn about the axis of the pivot 106 relatively to the jaw 83a from a relatively open position at the time the corresponding roller 100 or 101, presently to be described, enters the cavity 82 to a relatively closed position when the hook moves outwardly. The jaws are shown in their relatively closed position in Figure 13 and in their relatively open position in Figure 14. The provision of the pivoted jaw 84a insures free movement of the corresponding roller into and out of the cavity when the hook is in the position of Figure 14 while also insuring proper operation at all other times. Pivoted to the body 85 at 107 is a lever 108. The lever has a short upwardly projecting arm 109 and two laterally projecting arms 110 and 111. The arm 110 carries at its extremity a cam following roller 112. The arm 111 cooperates with a stop-block 113 connected with the body 85. A coil spring 114 normally urges the lever 108 to turn in the counterclockwise direction, viewing Figures 13 and 14, to a position in which

the arm 111 engages the under face of the block 113, as shown in Figure 13. The movable jaw 84a has a portion 115 adapted to cooperate with the arm 109 of the lever 108 as will be presently explained. A cam 116 is fixed to the frame and lies in the path of the roller 112 during oscillation of the hook.

When the roller 112 is out of engagement with the cam 116 the spring 114 maintains the lever 108 in the position of Figure 13. When the lever 108 is in that position the arm 109 engaging the portion 115 of the movable jaw 84a holds the jaw up in its relatively closed position. As the hook 77 moves to the right, viewing Figures 13 and 14, the roller 112 rides up on the cam 116 causing the lever 108 to turn in the clockwise direction about the axis of the pivot 107 and moving the arm 109 out of alignment with the portion 115 of the jaw 84a as shown in Figure 14 thus permitting the jaw 84a to turn somewhat in the clockwise direction about the axis of the pivot 106 to its relatively open position. As the hook 77 moves back toward the left in the counterclockwise direction about the axis of the bearings 90-91, viewing Figures 13 and 14, the roller 112 rides off of the cam 116 permitting the spring 114 to return the lever 108 to the position of Figure 13 in which the arm 109 lies against the under surface of the block 113 and the arm 109 cooperating with the portion 115 of the jaw 84a pushes that portion of the jaw upwardly causing the jaw to turn in the counterclockwise direction about the axis of the pivot 106 to its relatively closed position as shown in Figure 13 in which the opposed faces of the jaws 83a and 84a are almost parallel.

The reversing hooks 76-77 have pins 94-95 extending into the bores 87 thereof for connection to adjustable pitmans 96-97 extending to crank-pins 98-99 eccentrically fixed to the cranks 60-75. The cavities 82 of the reversing hooks 76-77 oscillate, as above explained, in the respective paths of complementary rollers 100-101 journaled on brackets 102-103 depending from and fixed to the under side of the table 28. The reversing hooks 76-77 alternately engage the rollers 100-101 while the rack 37 is disengaged from the split driving pinion 38-39 and thus operatively displace the table 38 during the reversal period of movement so that this may be extended and controlled to avoid excess stress and wear. The operation of the parts will be presently described.

The gears 57-78 are always in mesh and are mounted for opposite rotation in alignment on parallel shafts 58-73 respectively. On the inner ends of these shafts 58-73 are fixed crank arms 60-75 carrying the crank-pins 98-99 which are connected to reversing hooks 76-77 (Figure 9) by adjustable connecting rods or pitmans 96 and 97. These hooks 76-77 are mounted for oscillation about pins 92-93 within the limits A to C and A' to C'. The reversing hooks 76-77 assume the same relative opposite positions at the same instant so that the hook 76 is at A position when the hook 77 is at A' position. The slotted inclined jaws 82 of the hooks 76-77 receive the hanger rollers 100 and 101, respectively, which are disposed in the path thereof. A hanger bracket 102 and 103 and their rollers 100 and 101 are provided for each end of the bed 28. The rollers 100-101 are rotatively mounted on their hangers 102-103 which are fixed permanently to the underside of the bed 28.

Now, then, the principal reversing gears 57-78 run in mesh with each other and absorb the

strain of reversing the bed 28. These gears preferably run in oil and a transmission case (not shown) may be attached to the frame 10 for that purpose. The gear 72 is fixed to the inner end of the shaft 13 and is the same pitch and diameter as gears 57-78. The purpose of gear 72 is to drive the shifter gear 38. The gear 56 is a ring gear fixed to the gear 57, and corresponds in pitch and diameter therewith. The gear 56 drives the pinion 55 which is fixed for rotation on the shaft 46 that extends inwardly so that the shifter gear 39 may be fixed for rotation therewith on its inner extremity.

The shifter gears 38-39 have identical centers, but are free to turn oppositely and shift longitudinally together with the shaft 46. The gears 38-39 are longitudinally shifted with the shaft 46 while the bed 28 is at either end of travel by a cam controlled shifter lever 67 actuated and controlled by a barrel or cylindrical cam 66. The purpose of the shifter gears 38-39 is to drive the bed 28 by means of the rack 37 during printing and inking strokes of the press at a uniform speed after and before the reversing strokes occur.

The problem of reversing a printing bed may be advantageously explained by reference to the diagrammatic stroke diagram shown in Figure 12. From C to D is the printing stroke and from D to E is the decelerated movement to a virtual stop at E when acceleration is started to reach peak at F. From F to A is the inking stroke, from A to B there is deceleration, and then acceleration from B to C to complete the bed stroke circuit. During C to D and A to F the linear bed speed must be uniform and as shifter gears 38-39 are shifted into mesh with the rack 37, each must turn toward the bed directional travel when aligned with the bed rack 37.

Starting with the hanger roller 101 in reversing hook 77 at B' in Figure 3, the bed 28 is advanced to hook position A' which is the extent of travel of the bed 28 as the gears 57-78 turn one-quarter ($\frac{1}{4}$) turn and there the hook 77 takes position A'. In the next one-quarter ($\frac{1}{4}$) turn of gears 57-78, the bed 28 is advanced to the position corresponding with the hook 77 at B' in Figure 3 while the rack 37 has been enmeshed with shifter gear 39 exactly above or in vertical alignment with the shifter shaft 46. At the time the pinion 39 meshes with the rack 37, disengagement of hanger roller 101 with reversing hook 77 begins to occur. As gears 57-78 advance another one-quarter ($\frac{1}{4}$) turn the hook 77 takes position C' in Figure 4 and the bed 28 has then traversed one-half of its linear stroke which centers it above position D in Figure 4. During the next one-quarter ($\frac{1}{4}$) turn, the roller 100 has become engaged in hook 76 at C and the rack 37 leaves point D when in the next quarter ($\frac{1}{4}$) turn the bed 28 reaches its extreme position to the left opposite to the position shown in Figure 4, with the hook 76 at A. At this point, the shaft 46 is shifted to present shifter gear 38 in alignment with the rack 37 while the gear 39 moves inwardly to clear the path of the rack 37. The hook 76 now advances to B where the rack 37 meshes with the shifter gear 38 and roller 100 becomes disengaged from the hook 76 in the next one-quarter ($\frac{1}{4}$) turn of gears 57-78 so that the hook 76 takes the position C and the table 28 is again at the mid-point of its travel over the shaft 46 at D. In the next one-quarter ($\frac{1}{4}$) turn of the gears 57-78, the bed 28 is advanced to a position where the hook

77 has engaged the hanger roller 101 at B' and the rack 37 leaves the shifter gear 38.

The shaft 46 now shifts outwardly to present shifter gear 39 in alignment with the rack 37, and the bed circuit is complete. It will now be seen that one-half (1/2) revolution of gears 57-78 are necessary to complete each bed reversal and another one-half (1/2) revolution of gears 57-78 is required to complete either one printing or inking stroke; consequently, each reversal requires one-half (1/2) revolution, and one-half (1/2) revolution for a linear stroke effecting inking or printing. Therefore, two complete turns of gears 57-78 are required to produce the complete printing circuit.

Now, then, by increasing distance wherein the reversal stroke takes place in the manner described herein, appreciably less strain will be imparted to the reversing gears 57-78 and, therefore, they will be subjected to less wear. By reason of the large and identical pitch and diameters of gears 57, 78, and 72, more teeth will bear the reversal strain than in other bed motions. Further, this arrangement reduces the number of gear tooth playpoints to a minimum owing to the directness of their employment and their small number. By having the shifter gears 57-78 on identical centers, perfect work balance is obtained and, therefore, smooth operation results. The straight line bearing and gear teeth play points afforded by the structural arrangement of parts, reduces the diagonal stresses on the bed 28 and relieves its supporting tracks 13, 14, 15, 16 and aligning gibs 104-105 (Figure 7) from stresses and strains to the end of promoting long smooth operation.

This application is in part a continuation of my co-pending application Serial No. 560,949, now abandoned.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a device of the character described, the combination with a frame of a reciprocable member on said frame, means for displacing said reciprocable member intermediate its extreme limits of movement and oscillatable means for operatively displacing said reciprocable member when said first mentioned means are rendered inoperative, said oscillatable means having a slot receiving a portion of said reciprocable member, said oscillatable means having means whereby the transverse dimension of the mouth of said slot is enlargeable when said portion of said reciprocable member passes therethrough.

2. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means having a slot receiving a portion of said reciprocable member, the transverse dimension of the mouth of said slot being enlargeable, and means operable when said portion of said reciprocable member passes

through said slot for enlarging the transverse dimension of the mouth of said slot.

3. In a device of the character described, the combination with a frame of a reciprocable member on said frame, means for displacing said reciprocable member intermediate its extreme limits of movement and oscillatable means for operatively displacing said reciprocable member when said first mentioned means are rendered inoperative, said oscillatable means comprising opposed parts spaced apart to form a slot therebetween to receive a portion of said reciprocable member, said parts being movable relatively to each other to enlarge the mouth of said slot when said portion of said reciprocable member passes therethrough.

4. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising opposed parts spaced apart to form a slot therebetween to receive a portion of said reciprocable member, said parts being movable relatively to each other to enlarge the mouth of said slot, and means connected with said frame for so moving said parts when said portion of said reciprocable member passes therethrough.

5. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising opposed parts spaced apart to form a slot therebetween to receive a portion of said reciprocable member, said parts being movable relatively to each other, a cam follower on one of said parts and a cam connected with said frame and lying in the path of said follower during oscillation of said oscillatable means for moving the part carrying the cam follower relatively to the opposed part to enlarge the mouth of said slot when said portion of said reciprocable member passes therethrough.

6. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising opposed parts spaced apart to form a slot therebetween to receive a portion of said reciprocable member, said parts being pivotally connected to each other and being relatively movable about the axis of their pivotal connection to enlarge the mouth of said slot, and means connected with said frame for so moving said parts when said portion of said reciprocable member passes therethrough.

7. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising opposed

parts spaced apart to form a slot therebetween to receive a portion of said reciprocable member, said parts being pivotally connected to each other and being relatively movable about the axis of their pivotal connection to enlarge the mouth of said slot, a cam follower on one of said parts and a cam connected with said frame and lying in the path of said follower during oscillation of said oscillatable means for moving the part carrying the cam follower relatively to the opposed part about the axis of the pivotal connection between said parts to enlarge the mouth of said slot when said portion of said reciprocable member passes therethrough.

8. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising a primary member and a secondary member pivoted to said primary member, said members having opposed parts spaced apart to form a slot therebetween to receive a portion of said reciprocable member, said secondary member being pivotally movable relatively to said primary member about the axis of the pivotal connection between said primary and secondary members to enlarge the mouth of said slot, and means for so moving said secondary member relatively to said primary member when said portion of said reciprocable member passes through the mouth of said slot.

9. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising a primary member and a secondary member pivoted to said primary member, said members having opposed parts spaced apart to form a slot therebetween to receive a portion of said reciprocable member, said secondary member being pivotally movable relatively to said primary member about the axis of the pivotal connection between said primary and secondary members to change the width of the mouth of said slot, an operating device pivoted to said primary member and cooperating with said secondary member upon being turned about the axis of its pivotal connection with said primary member to so move said secondary member relatively to said primary member and means for moving said operating device to bring about enlargement of the mouth of said slot when said portion of said reciprocable member passes through the mouth of said slot.

10. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising a primary member and a secondary member pivoted to said primary member, said members having opposed parts spaced apart to form a slot therebetween to receive a portion of said reciprocable member, said secondary member being pivotally movable relatively to said primary

member about the axis of the pivotal connection between said primary and secondary members to change the width of the mouth of said slot, a lever pivoted to said primary member having an arm cooperating with said secondary member upon turning of the lever about the axis of its pivotal connection with said primary member to so move said secondary member relatively to said primary member, said lever also having a second arm, and means cooperating with said second arm during oscillation of said oscillatable means to turn said lever to bring about enlargement of the mouth of said slot when said portion of said reciprocable member passes through the mouth of said slot.

11. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means comprising a primary member and a secondary member pivoted to said primary member, said members having opposed parts spaced apart to form a slot therebetween to receive a portion of said reciprocable member, said secondary member being pivotally movable relatively to said primary member about the axis of the pivotal connection between said primary and secondary members to change the width of the mouth of said slot, a lever pivoted to said primary member having an arm cooperating with said secondary member upon turning of the lever about the axis of its pivotal connection with said primary member to so move said secondary member relatively to said primary member, said lever also having a second arm, a cam follower carried by said second arm, stop, means resiliently urging said lever against said stop, causing said secondary member to be disposed relatively to said primary member so that the width of the mouth of said slot is relatively narrow, and cam means connected with said frame and lying in the path of said follower during oscillation of said oscillatable means to turn said lever to bring about enlargement of the mouth of said slot when said portion of said reciprocable member passes through the mouth of said slot.

12. In a device of the character described, the combination with a frame of a rectilinearly reciprocable member on said frame, gear means for displacing said rectilinearly reciprocable member intermediate its extreme limits of movement and oppositely moving synchronously timed angularly oscillatable means for operatively displacing said rectilinearly reciprocable member when said gear means are rendered inoperative, said angularly oscillatable means each having a slot receiving a portion of said rectilinearly reciprocable member, said oscillatable means having means whereby the transverse dimension of the mouth of each slot is enlargable when said portion of said rectilinearly reciprocable member passes therethrough.

13. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means separate from the shaft for rotating the second mentioned gear in the direction of rotation op-

11

posite that in which the shaft is rotated and shifting means for rendering the first mentioned gear and the second mentioned gear alternately operative for displacing said oscillatable member.

14. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means separate from the shaft for rotating the second mentioned gear in the direction of rotation opposite that in which the shaft is rotated, means holding both gears against movement relatively to the shaft in the axial direction and means for shifting the shaft in the axial direction to render the respective gears alternately operative for displacing said oscillatable member, the means for rotating the shaft being arranged so as to be operative throughout the range of axial movement of the shaft.

15. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means separate from the shaft for rotating the second mentioned gear in the direction of rotation opposite that in which the shaft is rotated, oppositely moving synchronously timed oscillatable means for operatively displacing the oscillatable member at the ends of its stroke, means on the oscillatable member for connection with said oscillatable means when both of said gears are inoperative with respect to the oscillatable member and shifting means for rendering the first mentioned gear and the second mentioned gear alternately operative for displacing the oscillatable member intermediate the ends of its stroke.

16. In a device of the character described, the combination with a frame of a reciprocable member on said frame, means for displacing said reciprocable member intermediate its extreme limits of movement, oscillatable means for operatively displacing said reciprocable member when said first mentioned means are rendered inoperative, said oscillatable means having an elongated slot having a substantially straight side, and means on said reciprocable member entering said slot and riding along said substantially straight side thereof when the oscillatable means are operative and during a portion of the time when said first mentioned means are operative.

17. In a device of the character described, the combination with a frame of a reciprocable member on said frame, parallel shafts journalled for support on said frame, intermeshing gears for driving said shafts in opposite directions at the same speed, oscillatable means operatively connected to said shafts, a shifter shaft journalled for support on said frame, a double gear on said shifter shaft for driving said reciprocable member, a gear on one of said parallel shafts for driving said double gear to reciprocate said reciprocable member intermediate its extreme limits of travel, a shifter rotating gear in operative connection with said first named intermeshing gears to control the meshing position of said double gear, means on said reciprocable member for connection with said oscillatable means for

12

reversing said reciprocable member when said double gear is inoperative for displacing said reciprocable member, said oscillatable means including jaw means forming an elongated slot having a substantially straight side, and roller means carried by said reciprocable member in the path of said slot so as to ride along said substantially straight side thereof and during a portion of the time when said double gear is operative.

18. In a device of the character described, the combination with a frame of a reciprocable member on said frame, parallel shafts journalled for support on said frame, intermeshing gears for driving said shafts in opposite directions at the same speed, oscillatable means operatively connected to said shafts, a shifter shaft journalled for support on said frame, a double gear on said shifter shaft for driving said reciprocable members, a gear on one of said parallel shafts for driving said double gear to reciprocate said reciprocable member intermediate its extreme limits of travel, a shifter rotating gear in operative connection with said first named intermeshing gears to control the meshing position of said double gear, means on said reciprocable member for connection with said oscillatable means for reversing said reciprocable member when said double gear is inoperative for displacing said reciprocable member, said oscillatable means including jaw means forming elongated slots each having a substantially straight side, roller means carried by said reciprocable member in the paths of said slots so as to ride along said substantially straight sides thereof and during a portion of the time when said double gear is operative, crank arms on said parallel shafts and adjustable pitmans interposed between said crank arms and oscillatable means.

19. In a device of the character described, the combination with a frame of a reciprocable member on said frame, gear means for displacing said reciprocable member intermediate its extreme limits of movement, oppositely moving synchronously timed oscillatable means for operatively displacing said reciprocable member when said gear means are rendered inoperative, said oscillatable means including jaw means forming elongated slots each having a substantially straight side, and roller means carried by said reciprocable member in the paths of said slots so as to ride along said substantially straight sides thereof and during a portion of the time when said gear means are operative.

20. In a device of the character described, the combination with a frame of a reciprocable member on said frame, gear means for displacing said reciprocable member intermediate its extreme limits of movement, oppositely moving synchronously timed oscillatable means for operatively displacing said reciprocable member when said gear means are rendered inoperative, said oscillatable means including jaw means forming elongated slots each having a substantially straight side, roller means carried by said reciprocable member in the paths of said slots so as to ride along said substantially straight sides thereof and during a portion of the time when said gear means are operative, crank arms operatively driven by said gear means and adjustable pitmans interposed between said crank arms and oscillatable means.

21. In a device of the character described, the combination with a frame of a reciprocable member on said frame, gear means for displacing said

reciprocable member intermediate its extreme limits of movement, oppositely moving synchronously timed oscillatable means for operatively displacing said reciprocable member when said gear means are rendered inoperative, said oscillatable means including jaw means forming elongated slots, each having a substantially straight side, roller means carried by said reciprocable member in the paths of said slots so as to ride along said substantially straight sides thereof and during a portion of the time when said gear means are operative, crank arms operatively driven by said gear means and adjustable pitmans interposed between said crank arms and oscillatable means.

22. In a device of the character described, the combination with a frame of a reciprocable member on said frame, gear means for displacing said reciprocable member intermediate its extreme limits of movement, oppositely moving synchronously timed oscillatable means for operatively displacing said reciprocable member when said gear means are rendered inoperative, said oscillatable means including jaw means forming elongated slots each having a substantially straight side, roller means carried by said reciprocable member in the paths of said slots so as to ride along said substantially straight sides thereof and during a portion of the time when said gear means are operative, crank arms operatively driven by said gear means, adjustable pitmans interposed between said crank arms and oscillatable means and shifting means for rendering said gear means operative for alternately displacing said reciprocable member in opposite direction.

23. In a device of the character described, the combination with a frame of a reciprocable member on said frame, means for displacing said reciprocable member intermediate its extreme limits of movement, angularly oscillatable means for operatively displacing said reciprocable member when said first mentioned means are rendered inoperative, said angularly oscillatable means having an elongated slot having a substantially straight side and means on said reciprocable member entering said slot when the angularly oscillatable means are operative so as to ride along said substantially straight side of said slot and during a portion of the time when said first mentioned means are operative.

24. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft,

means for rotating the second mentioned gear in the direction of rotation opposite that in which the shaft is rotated and shifting means for rendering the first mentioned gear and the second mentioned gear alternately operative for displacing said oscillatable member.

25. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means for rotating the second mentioned gear in

15 the direction of rotation opposite that in which the shaft is rotated, means holding both gears against movement relatively to the shaft in the axial direction and means for shifting the shaft in the axial direction to render the respective gears alternately operative for displacing said oscillatable member, the means for rotating the shaft being arranged so as to be operative throughout the range of axial movement of the shaft.

26. In a device of the character described, the combination with a frame of an oscillatable member on the frame, a shaft, means for rotating the shaft in one direction of rotation, a gear on the shaft and connected therewith so as to rotate therewith when the shaft rotates, another gear on the shaft rotatable relatively to the shaft, means for rotating the second mentioned gear in the direction of rotation opposite that in which the shaft is rotated, oppositely moving synchronously

35 oscillatable means for operatively displacing the oscillatable member at the ends of its stroke, means on the oscillatable member for connection with said oscillatable means when both of said gears are inoperative with respect to the oscillatable member and shifting means for rendering the first mentioned gear and the second mentioned gear alternately operative for displacing the oscillatable member intermediate the ends of its stroke.

Certificate of Correction

Patent No. 2,517,210

August 1, 1950

ARTHUR J. JENNER

It is hereby certified that error appears in the printed specification of the above numbered patent requiring correction as follows:

Column 1, line 48, for "straight" read *straight*; column 3, line 34, for the words "period of" read *period or*; line 56, for "sleeve and" read *sleeve end*; column 10, line 40, before "stop" insert *a*;

and that the said Letters Patent should be read as corrected above, so that the same may conform to the record of the case in the Patent Office.

Signed and sealed this 28th day of November, A. D. 1950.

[SEAL]

THOMAS F. MURPHY,
Assistant Commissioner of Patents.
